UNITED STATES PATENT OFFICE.

CARL CULMAN, OF ST. LOUIS, MISSOURI.

JEWEL-SETTING CUTTER.

No. 834,457.

Specification of Letters Patent.

Patented Oct. 30, 1906.

Application filed September 14, 1905, Serial No. 278,511.

To all whom it may concern:

Be it known that I, CARL CULMAN, a citizen of the United States, residing at St. Louis, in the State of Missouri, have invented 5 certain new and useful Improvements in Jewel-Setting Cutters; and I do declare the following to be a full, clear, and exact description of the invention, such as will enable others skilled in the art to which it appertains to make and use the same.

This invention relates to jewel-setting cutters.

The object of the invention is to provide a device of this character with which settings 15 or seats of varying diameter may be drilled or cut for setting jewels or for other purposes.

A further object is to provide a device of this character which may be used in the tail-stock, turret-head, or slide-rest of lathes.

20 With the above and other objects in view the invention consists of certain novel features of construction, combination, and arrangement of parts, as will be hereinafter described and claimed.

25 In the accompanying drawings, Figure 1 is a side view of a lathe, showing the tool applied to the tail-stock thereof. Fig. 2 is an enlarged detail side view of the tool removed from the lathe. Fig. 3 is a longitudinal ver-

30 tical sectional view of the same. Fig. 4 is a cross-sectional view on a line of the set-screw. Fig. 5 is an end view of the tool. Fig. 6 is a side view of a modified form of tool, and Fig. 7 is an end view of the same.

35 Referring to the drawings by numerals, 1 denotes the tool, consisting of a body portion or shank 2, which is here shown as slightly tapered toward its inner or attaching end and having its opposite end split or bifurcated, as shown at 3. Through the tool at the inner end of the bifurcation or split is formed a transversely-disposed aperture 4.

40 On the bifurcated end of the tool are formed the bits or cutters 5, one of which is arranged on each side of the split or bifurcation and in juxtaposition to the edge of the same. The cutters, as shown in Figs. 1 to 5 of the drawings, have their cutting edges 6 arranged on the outer side of the bits in position to cut out a seat or setting corresponding to the shape and size of the jewel to be set.

In one side of the tool near the cutting

edge of the same is arranged a set-screw 7, said screw being arranged at right angles 55 to the bifurcation or split, and is adapted to be screwed through one half of the tool and into engagement with the split surface of the other half, whereby when the screw is screwed inwardly the bifurcated ends of the tool 60 will be sprung or forced apart more or less, thus separating the bits or cutters 5 to a greater or less degree, causing them to cut or drill settings or seats of varying diameters.

By providing the transversely-disposed 65 aperture 4 the elasticity or yielding qualities of the bifurcated ends of the tool will be increased, and the danger of breaking said ends will be diminished.

In Figs. 6 and 7 of the drawings is shown a 70 modified construction of the tool. In this instance the bits or cutters 8 are formed in juxtaposition to the outer surface of the tool and at substantially diametrically opposite points, thus forming between them a space 75 which is increased or diminished by means of the set-screw 7, as will be understood. The cutting edges 9 of the bits or cutters 8 are arranged on the inner side of the cutters, as shown. When the cutters or bits are ar- 80 ranged as last described, the tool is adapted for use for outside cutting, burnishing, &c.

From the foregoing description, taken in connection with the accompanying drawings, the construction and operation of the invention 85 will be readily understood without requiring a more extended explanation.

Various changes in the form, proportion, and the minor details of construction may be resorted to without departing from the principle or sacrificing any of the advantages of 90 this invention.

Having thus described my invention, what I claim as new, and desire to secure by Letters Patent, is—

95 In a tool of the character described, the combination with a tapering stem or shank having a split or bifurcated outer end and a transversely-disposed passage formed therethrough at the inner end of said bifurcation, of 100 a pair of cutters formed on said bifurcated end of the shank, said cutters being arranged on each side of said bifurcation, and adapted to be expanded, a set-screw arranged in one side of the bifurcated end of the shank at right 105 angles to said bifurcation, the inner end of

said screw bearing on the opposite side of the bifurcated end, whereby upon the adjustment of the screw inwardly or outwardly, said bifurcated ends of the shank and the cutters thereon may be separated to a greater or less degree, substantially as described.

In testimony whereof I have hereunto set

my hand in presence of two subscribing witnesses.

CARL CULMAN.
